UNITED STATES PATENT OFFICE

WILLIAM G. ABBOTT, JR., OF MILFORD, NEW HAMPSHIRE.

FLUID-PRESSURE APPARATUS.

1,102,222.

Specification of Letters Patent. Patented June 30, 1914.

Application filed August 22, 1912. Serial No. 716,445.

To all whom it may concern:

Be it known that I, WILLIAM G. ABBOTT, Jr., a citizen of the United States, and resident of Milford, in the county of Hillsboro and State of New Hampshire, have invented new and useful Improvements in Fluid-Pressure Apparatus, of which the following is a specification:

This invention relates to compressors, pumps, motors and the like, and particularly to apparatus of this general class in which fluid compression or suction is maintained by relative movement between a helical passage and a body of fluid held in position eccentrically to the axis of said helical passage by centrifugal force.

In the embodiments of the invention herein illustrated the invention comprises two rotors, one of which is hollow and incloses the other. The outer rotor contains a body of liquid such for example as mercury or water, which revolves with the outer rotor and consequently is under pressure due to the action thereon of centrifugal force, while the inner rotor is made with a helical or spiral passage surrounding the axis of said rotor and extending lengthwise thereof. The inner rotor is eccentrically supported relatively to the body of fluid within the outer rotor so that a portion of each convolution of the helical passage is submerged in the body of fluid. Herein I have shown my invention as embodied in an air compressor or the like with both rotors driven in the same direction, but in such manner that the partially submerged helical passage of the inner rotor revolves relatively to the body of fluid that is under pressure from centrifugal force. As a result, each convolution of the helical passage is occupied and closed in part by a body of the fluid which occupies the submerged portion of the convolution, while the remaining portion of each convolution is occupied by air or other fluid that is being compressed. As the helical passage rotates relatively to the fluid the portions of the fluid occupying the submerged parts of the convolutions do not rotate with the helical passage but traverse the latter so that these bodies of fluid, which are segmental in form, act as pistons to propel the air, or other matter being compressed, along the helical passage from the inlet end to the discharge end thereof.

In the accompanying drawings: 55
Figure 1 is a central, longitudinal, sectional view of an air compressor or the like embodying one form of my invention; Fig. 2 is a section on lines 2—2 of Fig. 1; Fig. 3 is a central, vertical, sectional view of an air compressor or the like, embodying another form of my invention; Fig. 4 is a central, vertical, sectional view of still another form of air compressor or the like embodying the invention, and containing two inner rotors 60 of the general character shown in Fig. 3; Fig. 5 is a section on line 4—4 of Fig. 4 but with the inner rotors removed; Fig. 6 is an elevation of the outlet end of one of the inner rotors of the compressor shown in Fig. 70 4; and Fig. 7 is an elevation of the inlet end of the rotor shown in Fig. 5.

Having reference to Figs. 1 and 2 of the drawings, A represents the frame of the compressor made with bearings a, in which are journaled hollow trunnions b provided on the ends of the outer rotor B. The frame A is also provided with bearings a' for a hollow shaft c, on which is fixed an inner rotor consisting of two drums C, each in the 75 form of a truncated cone provided upon its periphery with a helical blade c', the blade c' on one drum being right-handed in pitch, and the blade e' on the other drum being left-handed.

The outer rotor B contains a body b' of water, mercury or other suitable liquid which rotates with the rotor B. When the latter is operated as hereinafter described centrifugal force acts to form the liquid body b' into a cylindrical shape under centrifugal pressure, proportionate to the speed at which rotor B is driven. This liquid cylinder b' rotates around the axis of the outer rotor B, which is offset relatively to the axis 80 of the inner rotor C, so that the convolutions of the helical passages c², formed between the blades c' upon the exterior of each inner rotor C, are only partially submerged in the liquid cylinder b'. 85

One of the trunnions of rotor B has fixed to it a pulley b³, by which said rotor is driven from a suitable source of power, while the shaft c is provided with a pulley c³ by which it is driven. 90

The two rotors B and C are driven in the same direction and at such speeds that the peripheries of the two drums of the inner 95

100

105

5 rotor, which carry the blades c' , travel at approximately the same speed as the inner surface of the liquid cylinder b' , the purpose of the rotation of the casing being to maintain the liquid in proper position and under centrifugal pressure, and the purpose of the rotation of the inner rotor being to propel the air or other matter from one end of the helical passage to the other in cooperation with the liquid.

10 With the blades c' arranged as shown in the drawings, the rotors B and C will be driven in the direction indicated by the arrows in Fig. 2, and when the apparatus is in 75 operation the effect is the same as if the partially submerged inner rotors were rotating within a stationary cylinder composed of liquid under pressure, and as will be clear the only liquid displacement occasioned by 80 20 the inner rotors directly is a lateral flow thereof due to the liquid pistons traversing the helical passage.

Since a portion of the length of each convolution of the helical passages c^2 is completely submerged, occupied and closed by a body of liquid, and since the relative movement between the body b' and the helical passage causes this body to travel from one end of the helical passage to the other, it 90 30 will be clear that said bodies serve as pistons to propel ahead of them the air which occupies the crescent shaped unsubmerged portion of each convolution of the helical passage c^2 . It will also be clear that eventually these crescent shaped bodies of air will be discharged into the chamber b^4 between the two drums C , and thence through port p and hollow shaft e , to a receptacle (not shown) into which the air is 95 40 compressed. Air is supplied to the rotors C through the hollow trunnions b from the atmosphere.

The air enters first the inlet end of the helical passage when it is out of the body of liquid b' , and as the inner rotor turns, a crescent shaped volume of air, at atmospheric pressure is taken in and shut off as the inlet end of the helical passage is again immersed. As this confined body of air 105 50 moves toward the central chamber b^4 at the outlet end of the helical passage, propelled by the fluid piston formed behind it in the wholly immersed segment of the helix, it is gradually and steadily compressed by the 110 55 gradual reduction in the capacity of the helical convolutions as they approach the outlet end, due to reduction in width of the helical passage, as shown in the drawings. As the capacity of the convolutions decreases, the increasing pressure of the air 115 60 trapped in the convolutions tends to distort or displace the surface of the fluid cylinder b' , to compensate for which the diameters of the drums C are gradually enlarged from 120 65 the inlet toward the outlet ends, so that said

passage will be immersed substantially uniformly throughout its length. The gradual constriction of the helical passage, and the taper of the drums C , are so proportioned as to maintain a practically constant immersion from the first turn in the helix to the last, whereby the surface of the fluid cylinder will not be unevenly disturbed. 70

The pressures secured by this apparatus will depend upon the artificial hydraulic or fluid head or pressure due to the action of centrifugal force on the revolving body of fluid. The total attainable air compression will be determined by difference in the pressure of the fluid in the first and last convolutions, and the higher the speed of revolution of the centrifugally held fluid body, the greater will be the artificial fluid head or pressure, and the greater the compression attainable. 75 80 85

Should it be desired to use the device for a suction pump, the taper of the inner rotors may be reversed, and the air removed from the central space and forced outward against atmospheric pressure, the directions of revolution of the inner and outer rotors being properly arranged. 90

Ordinarily surface friction will be sufficient to drive the liquid cylinder, but for special purposes blades or vanes on either the inner or outer rotor may be used as auxiliary means to keep the fluid cylinder revolving. Such expedient might be particularly desirable when one of the rotors is held stationary. In such case some auxiliary driving means might be required on the revolving member to overcome the friction between the revolving liquid and the stationary member. 100

The revolution of the liquid cylinder however maintained, as by the revolving casing, or otherwise, determines the effective pressure obtainable with a given immersion. The revolution of the helix in the liquid cylinder determines the speed of the pumping. To 105 110 reduce the friction as far as possible, the speed of the different parts are made preferably near together.

It will be understood that one helical passage may be employed or any number arranged in series; and that any number of pumps may be arranged in similar fashion if desired. The use of the multiple threads or blades, as shown in Fig. 1, two of which are symmetrically placed, possess advantages due to correct balancing of the parts resulting from the symmetrical arrangement. Such arrangement also insures the air being uniformly entrapped and discharged. 115 120

By reversing the action of the pump, a rotary fluid engine having desirable properties will result as will be readily understood.

In the form of my invention shown in Fig. 3 the hollow outer rotor is shown at B^2 and the inner rotor at C^2 , the latter being 130

formed with a helical passage c^3 tapering from its inlet end toward its outlet end, and partly filled by fluid from the body b' , forming fluid pistons b^8 . Rotor B^2 is made with 5 trunnions b journaled in bearings a , while the inner rotor C^2 is journaled eccentrically within the outer rotor and partially submerged in an annular body b' of water, mercury or the like, similar to the body b' of 10 Fig. 1. Near the outlet end of passage c^3 the rotor C^2 is made with two flanges d and d' , whose peripheries are submerged in body b' throughout their circumferences. The two flanges d and d' are separated so as to 15 provide a chamber d^8 between them with which communicates one end of passage d^6 , whose opposite end is connected through a port d^{10} in one wall of rotor B^2 , with the interior of one of the trunnions b , which is 20 made hollow to serve as an outlet conduit for the air or other fluid that is compressed. The disk d' not only forms with the flange d , a chamber in which the compressed air is 25 confined, but cuts off communication of the compressed air with the bearing of trunnion d^2 and obviates the necessity of packing that bearing. The disk d' prevents side thrust upon the rotor C^2 which would otherwise result by reason of the compressed air between the delivery end of the rotor and the 30 end wall of casing B^2 . By confining the air under pressure in chamber d^8 between the end of the rotor and the disk d' the pressure is balanced, and side thrust, with the consequent increase of friction and wear, is 35 wholly obviated. The same result is attained in the form of the invention shown in Fig. 1, where the adjacent ends of the rotors C , C , act each as an opposed member 40 for the other, to balance the pressure in the delivery chamber between the two rotors and prevent side thrust. A similar disk d' could, if desired, be used at the other end of rotor C^2 , between the small end of rotor C^2 and the 45 wall of B^2 . The trunnion d^2 of the rotor C^2 extends to the exterior of rotor B^2 and has fixed to it a pinion d^6 , in mesh with an internal gear d^4 provided on a pulley d^7 loosely mounted on one of the trunnions of rotor B^2 , 50 said pulley being driven from a source of power in the same fashion that the rotors C of Fig. 1 are driven relatively to the outer rotor.

The air or the like that is being 55 compressed enters rotor B^2 through an inlet opening d^8 which communicates with the chamber d^8 . From chamber d^8 the air or the like passes into passage c^3 within which it is compressed, and from which it is discharged 60 into chamber d^8 . From chamber d^8 the compressed air or the like passes through ports d^9 and d^{10} to any suitable receptacle. The two rotors B^2 and C^2 of this form of my invention while constructed differently have 65 essentially the same mode of operation as

either rotor C and rotor B of the form shown in Fig. 1.

Having reference now to the modifications shown in Figs. 4, 5, 6 and 7, B' represents the outer rotor which is provided with trunnions b^5 and b^6 , both made hollow to serve as conduits, the former to admit the air to the compressor and the latter to remove it therefrom. These trunnions, b^5 and b^6 , are journaled in bearings a^2 on the frame of the machine, and the trunnion b^6 is provided with a pulley b^7 through which the rotor B' is driven.

Within the rotor B' are arranged two liquid bodies b' of water, mercury or the like, corresponding to the body b' of Figs. 1, 2 and 3. These bodies b' are forcibly held at opposite ends of the rotor B' by centrifugal force, so that they are under pressure corresponding in degree to the velocity of the rotor, and in each body b' an inner rotor C' is partially submerged, said inner rotors being provided with trunnions journaled in bearings on the rotor B' , and provided with pinions C^4 meshing with a stationary pinion c^5 . As the rotor B' rotates in the direction of the arrow about the axis of trunnions b^5 and b^6 , the inner rotors C' not only travel around said axis but are rotated as indicated by arrows on their own axes by the pinions c^4 and c^5 .

Each inner rotor C' , which is fundamentally similar to rotor C^2 of Fig. 3, is made with a tapering helical passage c^2 , each convolution of which is occupied in part by a fluid piston b^8 forming part of the body b' . The rotation of each inner rotor C' on its own axis causes the fluid pistons b^8 to traverse the helical passage c^2 and to carry before them the air occupying the unsubmerged portion of each convolution. In Fig. 7 c^{21} indicates the inlet end of the helical passage of one of the inner pistons C' and, as will be clear, when said end is not submerged in the body b' with which it co-operates, it is free to receive air from the space b^9 that communicates with the hollow trunnion b^5 .

In Fig. 6 c^{21} indicates the discharge end of the helical passage c^2 , and this opening 115 co-operates with a slot b^{10} formed in the end of rotor B' , to discharge the compressed air from the helical passage c^2 through said slot into the hollow trunnion b^6 , with which the slot communicates. The slot b^{10} is concentric with the axis of the inner rotor and extends from a point just outside of the body b' at one side of said axis to a point just outside the same body b' at the opposite side of said axis, and is surrounded by a raised 120 boss or seat b^{11} against which the end of the rotor snugly fits. The boss b^{11} is not much longer than the slot b^{10} so that while the outlet end c^{21} is submerged in the body b' it is free and clear of the boss b^{11} and can dis- 125 130

charge the fluid piston b^s from the helical passage,—or rather, the helical passage can be withdrawn from or shed the fluid piston b^s while the discharge end c^{21} is passing 5 through the body b' .

I claim:

1. A hollow outer casing containing a body of liquid, means to maintain said body of liquid in position by centrifugal force, 10 a drum having a helical passage partially submerged in said centrifugally held body of liquid, an inlet passage communicating with one end of said helical passage and an outlet passage communicating with the 15 other end of said helical passage, said helical passage being of gradually diminishing capacity from its low pressure end toward its high pressure end, and said drum becoming progressively larger in diameter 20 from its low pressure end toward its high pressure end to compensate for the distortion of the surface of the fluid under the increased pressure resulting from said diminishing helical passage, and means to effect 25 feet a relative rotative movement between said drum and the body of liquid.
2. A hollow outer casing containing a body of liquid, means to maintain said body of liquid in position by centrifugal force, an 30 inner member having a helical passage partially submerged in said body of liquid, an inlet passage communicating with one end of said helical passage and an outlet passage communicating with the other end of 35 said helical passage, said helical passage being of gradually decreasing pitch from its low pressure end toward its high pressure end, and means to effect a relative rotative movement between said helical passage and 40 said body of liquid.
3. A hollow outer casing containing a body of liquid, means to maintain said body of liquid in position by centrifugal force, a drum having a helical passage partially 45 submerged in said centrifugally held body of liquid, a member opposed to the high pressure end of said drum, having its periphery submerged in said body of liquid and forming with the high pressure end of 50 said drum a pressure chamber adapted to counter-balance the pressure exerted on the end of said drum, an inlet passage communicating with one end of said helical passage

and an outlet passage communicating with the other end of said helical passage, one of 55 which opens into said pressure chamber.

4. A hollow outer casing containing a body of liquid, means to maintain said body of liquid in position by centrifugal force, a hollow shaft extending through said casing, 60 a drum mounted on said shaft having a helical passage partially submerged in said centrifugally held body of liquid, a member mounted on said shaft opposite to the high pressure end of said drum having its periphery submerged in said body of liquid and forming with the high pressure end of 65 said drum a pressure chamber adapted to counterbalance the pressure exerted on the end of said drum, an inlet passage and an 70 outlet passage communicating with the ends of said helical passage, one of which opens into the pressure chamber through said hollow shaft.

5. A hollow cylinder containing a body of 75 liquid, means to maintain said body of liquid in position by centrifugal force, a hollow shaft extending through said casing, two drums mounted on said shaft, each having a helical passage partially submerged in said 80 centrifugally held body of liquid, a passage communicating with the outer end of each helical passage, the adjacent ends of said drums being spaced apart to form a pressure chamber adapted to counterbalance the pressure 85 exerted on the opposed ends of said drums, and a passage opening into said pressure chamber through said hollow shaft.

6. A hollow cylinder containing a body of 90 liquid, means to maintain said body of liquid in position by centrifugal force, a hollow shaft extending through said casing, two drums mounted on said shaft, each having a helical passage partially submerged in said 95 centrifugally held body of liquid, a passage communicating with the outer end of each helical passage, and a single passage communicating with the adjacent high pressure ends of the helical passages of said drums through said hollow shaft. 100

Signed by me at Boston, Massachusetts, this seventeenth day of August, 1912.
